UNITED STATES PATENT OFFICE.

EDWIN A. HALL, OF HYDEPARK, MASSACHUSETTS.

SECTIONAL GAS-BURNER.

SPECIFICATION forming part of Letters Patent No. 741,130, dated October 13, 1903.

Application filed December 1, 1902. Serial No. 133,315. (No model.)

To all whom it may concern:

Be it known that I, EDWIN A. HALL, of Hydepark, in the county of Norfolk and State of Massachusetts, have invented certain new and useful Improvements in Sectional Gas-Burners, of which the following is a specification.

This invention relates to means for supplying an inflammable mixture, such as gas and air, to ranges or heaters in general, this invention having particular reference to the structure of the burner itself regardless of the means to be used in connection therewith for utilizing the heat generated.

15 The object of the invention is to provide an improved burner constructed in sections which may be independently controlled, thereby enabling the quantity of heat delivered to the range or its equivalent to be regulated as may be desired and also preventing the detonations which result from shutting off the supply of gas to a single large burner.

25 Further objects of the invention are to provide improvements in the couplings between the supply-pipes and the sections and to provide the sections of the burner with tops so formed as to prevent undue heating, and thus keep the interior of the conduit within the section relatively cool.

30 To these ends the invention consists in the construction and arrangement of parts substantially as hereinafter described and claimed.

35 Of the accompanying drawings, Figure 1 represents a plan view of a burner consisting of a plurality of sections, said figure illustrating the sections as constructed according to one embodiment of my invention. Fig. 2 represents an edge view of the burner shown 40 in Fig. 1 and showing also the pipe connections for supplying the inflammable mixture to the sections. Fig. 3 represents a detail section on line 3 3 of Fig. 1. Fig. 4 represents a detail section enlarged of one of the 45 packed couplings.

The same reference characters indicate the same parts in all the figures.

As shown in Figs. 1 and 2, the burner is represented as being formed of three sections 50 *a*, *b*, and *c*, arranged in juxtaposition and composed of hollow pipes or castings having perforated tops and formed with branches

the spaces between which are substantially equal. The several sections when arranged in their proper relative positions form a complete burner of relatively large area comprising two side members and an intermediate member each having branches, the spaces between all of the branches being substantially equal. The burner illustrated is in the form 55 of a circle, the two outer sections including also chords of the circle and short radii thereof, while the central section includes a diametrical bar terminating in bars in the form of arcs of the circle and intermediate 60 substantially parallel bars at right angles to the central diametrical bar. As above stated, the spaces between these bars or branches are substantially equal, so as to provide an equal distribution of heat. Each section is independently supplied with inflammable mixture, and for this purpose each said section is provided with a hub or nipple, as represented at *a'*, *b'*, and *c'*, respectively. Connecting supply-pipes are represented at *a*², *b*², 70 and *c*², said connecting-pipes having packed couplings *d* interposed between them and the nipples of the distributing-sections. Each of said connecting-pieces is provided with a controlling valve or cock, as represented at 75 *a*³, *b*³, and *c*³, the ends of the pipe beyond said cocks being connected with a supply-main *e*, having a suitable valve or cock. By means of the cocks *a*³, *b*³, and *c*³ the supply to the independent distributing-sections of 80 the burner may be varied or controlled according to the desires of the user, and by means of said cocks the supply may be shut off successively, so as to prevent a detonation, which commonly follows the shutting off 85 of the supply of gas to a large or spread-out distributing-burner.

The sectional gas-burner herein described is intended to be used in connection with a suitable air and gas mixing device, (not 90 shown,) so as to obtain the effect of the Bunsen burner at the perforations of the sections. To prevent the combustion from extending back into the supply-pipes, I provide the packed couplings *d*, above referred to. These 100 packed couplings, as shown in Fig. 4, contain a plurality of layers of disks of fine wire-gauze or its equivalent. The lower portion of each coupling is provided with a shoulder *d'*, and

on this a wire-gauze disk d^3 is laid. Then a ring d^2 , which fits the outer edge of the wire disk, is placed on top of it, and then another wire disk is supplied, then another ring and 5 another disk, and so on, until the space between the coupling is filled with the necessary number of screens. The perforations for the emission of the inflammable mixture are represented at f . Preferably the bars of the 10 burner are substantially rectangular in cross-section, but at the center of their tops are made thicker, the perforations leading through this thickened portion. Each side of the perforations of the bars are beveled or inclined, as indicated at g . This structure serves 15 to keep the top portion of the burner relatively cool, inasmuch as the quantity of metal is reduced, and the area of surface exposed to contact with the air is increased by thus beveling the bars. I prefer to form grooves or recesses h in the reduced top surfaces of the bars between the perforations f to further assist in keeping the top portion relatively cool.

I do not limit myself to the form of the sections here shown, as the same may be variously modified to suit different requirements. 25

I claim—

1. A sectional gas-burner comprising two side members or sections and an intermediate 30 member or section, the several members or

sections being provided with means for independently controlling the supply of fuel thereto, and all having branches, the spaces between the branches being substantially equal in area.

2. A sectional gas-burner comprising three members or sections having the outline form of a circle, the two outer sections including also chords of the circle and short radii thereof, the central section including a diametrical 40 bar terminating in bars in the form of arcs of a circle and intermediate substantially parallel bars or branches at right angles to the central diametrical bar, the spaces between the bars or branches being substantially equal to 45 provide an equal distribution of heat.

3. The combination with a burner-section, of a pipe for supplying inflammable mixture thereto, and a packed coupling between said pipe and the burner-section, said packed coupling containing a plurality of wire-gauze disks and spacing-rings interposed between said disks. 50

In testimony whereof I have affixed my signature in presence of two witnesses.

EDWIN A. HALL.
